CHANDELIER LIGHT FIXTURE
Joseph R. Ramsey, Jr., R.R. 1, Box 80,
Chesterstown, Md. 21620
Filed Nov. 23, 1964, Ser. No. 413,111
8 Claims. (Cl. 240—78)

The present invention relates to an electrical light fixture of the chandelier type, more particularly, to such a light fixture which is attached to the ceiling and includes several suspended parts with the electric wiring passing therethrough and being completely concealed from view.

The usual chandelier light fixture comprises a body member having a number of lamp elements mounted thereon with the chandelier being suspended from the ceiling by a chain. The electric wiring for the lamp elements is interwoven through the chain in an effort to conceal the wiring as much as possible. However, this wiring remains visible and hence detracts from the overall appearance of such light fixtures, particularly when the lamp elements simulate candles or other non-electric sources of illumination.

It is therefore the principal object of the present invention to provide a novel and improved chandelier light fixture.

It is a further object of the present invention to provide a novel and improved wiring arrangement for a chandelier light fixture.

It is another object of the present invention to provide a chandelier electric light fixture wherein the several lamps thereon are connected to a source of electricity through wiring which passes upwardly through the chandelier to the ceiling but is concealed from view.

It is an additional object of the present invention to provide a novel and improved arrangement for securing the ceiling dome onto the uppermost portion of a chandelier light fixture.

The objects of the present invention are achieved by the chandelier light fixture disclosed herein which comprises a plurality of candle simulated lamps on the ends of hollow supporting arms extending radially outwardly from a body member. The body member is hollow and has a ring at the top thereof which is also hollow and which communicates with the interior of the body member. The body member is supported by the ring upon a hook formed in the lower end of a hollow rod-like element, the upper end of which is secured to the ceiling. There are registering openings in the hook and the ring so that electric wires can extend from the lamps upwardly through the body and ring through the openings and then upwardly through the rod-like element to an electrical junction box mounted in the ceiling. Thus, while the light fixture disclosed herein is suspended by a ring and hook arrangement, the wire is completely concealed from view and assists to complete the illusion that the candle simulated lamps are not electric.

On the uppermost portion of the rod-like element there is slidably mounted a dome-shaped ceiling plate which is positioned against the ceiling to conceal the connection between the rod-like element and the junction box. An arrangement is provided within this ceiling plate for locking the ceiling plate in position on the rod-like element. This locking means is accessible from the exterior of the ceiling plate. Thus, when the chandelier lamp fixture has been installed, no indication remains of how the ceiling plate is secured in position nor is there any indication of the electric wires leading downwardly through the chandelier to the electric lamps.

Other objects and advantages of the present invention will be apparent upon reference to the accompanying description when taken in conjunction with the following drawings, wherein:

2

FIGURE 1 is an over-all perspective view of the chandelier light fixture of this invention, and looking upwardly from approximately the position of a person viewing the installed fixture;

5 FIGURE 2 is an exploded perspective view of the light fixture of FIGURE 1, with the body member being shown in vertical section;

FIGURE 3 is a vertical sectional view of the ceiling plate taken along the line 3—3 of FIGURE 4; and

10 FIGURE 4 is a top plan view of the ceiling plate of FIGURE 3 showing the locking arrangement therein.

Proceeding next to the drawing wherein like reference symbols indicate the same parts throughout the various views, a specific embodiment of this invention will be described in detail.

15 As may be seen in FIGURE 1, the chandelier light fixture disclosed herein essentially comprises a base 1, from which extend radially a plurality of circumferentially spaced supporting arms 2 having on their outer ends candle simulated lamps 3. Attached to the top of the body member 1 is a ring 4 which is supported upon a hook 5 formed on the lowermost portion of the rod-like supporting element 6. On the upper end of the rod-like element is a dish-shaped ceiling plate 7 which is positioned against the ceiling, as shown in the drawing.

20 The body member 1 is formed of wood, such as walnut, and may be turned to any desired shape and subsequently finished as desired. The body member 1 comprises a removable bottom 8 which encloses a hollow space 9 formed within the body member. The space 9 is cylindrical in shape and has a copper ring 10 lining the peripheral wall thereof. In the copper ring 10 are a plurality of openings 11 corresponding to the number of supporting arms 2 and registering with the inner ends 25 thereof, as shown in FIGURE 2.

The bottom 8 is removably secured to the body member 1 by a stud bolt 12 which is threaded into a channel bracket 13 secured by screws 14 to the top of the space 9, as may be seen in FIGURE 2. The lower portion of 30 the stud bolt 12 is threaded into a plate 15 which is similarly attached by screws 16 to the top surface 17 of the bottom 8. The bracket 13 and plate 15 are both made of a relatively soft, flexible material, metal or plastic, to permit alignment and adjustment of the bottom 8 with respect to body member 1.

35 A peripheral lip 18 is formed on the bottom edge of the body member 1 so as to enclose the top edge of the bottom 8 when it is secured in position.

Extending upwardly from the chamber 9 is a vertical 40 passage 19 which communicates at the top thereof with a cross passage 20 to form a T-shaped passage within the body member 1.

45 Extending radially outwardly from the body member 1 are the supporting arms 2 which may be shaped as desired and which are hollow. The inner ends 21 of the supporting arms 2 are soldered at 22 to the inner face of the copper ring 10. On the outer ends of the supporting arm are mounted electric lamps of any desired type, such as the candle simulated lamps 3 utilized in this embodiment.

50 The body member 1 is supported by the split ring 4 which has a tubular cross-section. The ends 23 of the ring 4 are pinched into the ends of the cross passage 20 when the ring is assembled to the body member. On the uppermost portion of the ring 4 on a side surface thereof there is an opening 24 which is for the passage of electric wiring, as will be subsequently described.

55 The ring 4 is suspended from the hook 5 which is provided with an opening 25 on the inner face thereof and positioned so as to register with the ring opening 24 when the ring is on the hook 5.

60 Both the ring 4 and the rod-like supporting element 6

are worked to look like wrought iron but are hollow. The element 6 may have a circular or square cross-section.

A threaded nipple 26 is brazed on the top end of the rod-like supporting element and is screwed into a threaded opening 27 in a mounting plate 28 which is secured by screws 29 to an electrical junction box 30 mounted in the ceiling.

The connection between the rod-like supporting element 6 and the electrical junction box 30 is concealed by the ceiling plate 7 which is lockingly positioned on the upper end of the rod-like supporting element 6 by a locking arrangement illustrated in detail in FIGURES 3 and 4.

The dome-shaped ceiling plate 7 has a central aperture 31 through which the rod-like element 6 is passed and conforming to the shape of the element 6. On one side of the aperture 31 an angle iron 32 is brazed to the inner surface of the ceiling plate and positioned so that a leg 33 of the angle iron is closely adjacent to the aperture 31. On the other side of the aperture 31 diametrically opposed from the angle iron 32 there is brazed a second angle iron having an inclined leg 34 which slopes toward the aperture 31, as may be seen in FIGURE 3. Positioned below the inclined plate leg 34 is a cylindrical dowel 35 which is mounted on a substantially U-shaped spring steel wire clip 36, the ends of which are soldered at 37 on the inner surface of the ceiling plate 7. The spring clip 36 exerts a downward force on the dowel 35 to urge the dowel into engagement with the inner surface of the ceiling plate.

Closely adjacent the central aperture 31 and through the other leg of the second angle iron is a small threaded opening 38 in which is threaded a set screw 39 the upper end of which contacts the dowel 35.

The lamps 3 are electrically connected to the junction box 30 by flexible electric wiring 40 which passes from each lamp 3 through its hollow supporting arm 2 into the chamber 9 where it joins the other wires 40 coming from the individual lamps. This electrical wiring, as indicated at 41, then passes upwardly through the passage 19, across passage 20, into the hollow ring 4, outwardly through the opening 24 into the opening 25, and then upwardly through the rod-like element 6 to the junction box 30. As is evident from FIGURE 1, when the light fixture is assembled with the body member 1 being supported from the rod-like element hook 5 by the ring 4, the wiring 41 is concealed from view since it passes from the ring 4 into the rod-like element 6 through the contacting opening 24 and 25. Thus, while the light fixture of this invention is suspended from a rigid supporting element, i.e. the rod-like element 6, the electric wires are completely concealed from view when passing through the physical connection between the ring 4 and the hook 5.

After the light fixture has been installed in position, it is then desired to slide the ceiling plate 7 upwardly on the rod-like element 6 into engagement with the ceiling and then lock the ceiling plate in this position. This locking is accomplished by threading the set screw 39 inwardly so as to urge the dowel 35 upwardly into wedging position between the inclined plate 34 and the rod-like element 6, such as is shown in FIGURE 3. The length of the set screw 39 is so selected that the outer end of the set screw is flush with the outer surface of the ceiling plate when the dowel 35 is wedged upwardly in its locking position. The outer surface of the ceiling plate may then be painted and the set screw will be concealed from the view of a person standing on the floor below the chandelier.

The entire effect of the set screw and the concealed wiring is to produce a chandelier type lighting fixture wherein the electrical connection and mounting members are all concealed from view. Accordingly, such light fixtures can simulate old-fashioned chandeliers where the illumination is achieved by candle simulated lamps or by lamps simulating other non-electric sources of illumination. Not only are the wiring and ceiling mounting connections com-

pletely concealed but the entire fixture rigidly and compactly constructed so as to be quickly installed. Further, the entire light fixture is rugged in construction although graceful in appearance.

It will be understood that this invention is susceptible to modifications in order to adapt it to different usages and conditions, and accordingly, it is desired to comprehend such modifications within this invention as may fall within the scope of the appended claims.

What is claimed is:

1. A chandelier light fixture comprising a hollow body member, a plurality of hollow supporting arms extending outwardly from said body member, electric light elements on the outer ends of said supporting arms, a ring having a tubular cross section and an opening thereinto connected to the upper portion of said body member and communicating with the interior thereof, a tubular rod-like element having means on the upper end thereof for securing said rod-like element to a ceiling and a hook on the lower end thereof with said ring being supported on said hook, an opening in said rod-like element, and flexible electrical conductors extending from said electric light elements through said supporting arms, said body member, said ring and the openings therein and in said rod-like element so as to be concealed from view when said chandelier light fixture is mounted in position from a ceiling.

2. A chandelier light fixture comprising a hollow body member, a plurality of hollow supporting arms extending outwardly from said body member, electric light elements on the outer ends of said supporting arms, a ring having a tubular cross section connected to the upper portion of said body member and communicating with the interior thereof, a tubular rod-like element having means on the upper end thereof for securing said element to a ceiling and a hook on the lower end thereof with said ring being supported on said hook, there being a first opening in the inner face of said hook adjacent said ring and a second opening in said ring registering with said first opening, and flexible electrical conductors extending from said electric light elements through said supporting arms, said body member, said ring and through said openings into said rod-like element so as to be concealed from view when said chandelier light fixture is mounted in position from a ceiling.

3. A chandelier light fixture comprising a hollow body member, a plurality of hollow supporting arms extending outwardly from said body member, candle simulated lamps on the outer ends of said arms, a ring having a tubular cross section connected to the upper portion of said body member and communicating with the interior thereof, a tubular rod-like element having means on the upper end thereof for securing said rod-like element to a ceiling and a hook on the lower end thereof with said ring being supported on said hook, there being a first opening in the inner face of said hook adjacent said ring and a second opening in said ring registering with said first opening, and flexible electrical conductors extending from said lamps through said supporting arms, said body member, said ring and through said first and second openings into said rod-like element so as to be concealed from view when said chandelier light fixture is mounted in position from a ceiling.

4. A chandelier light fixture comprising a hollow body member, a plurality of hollow supporting arms extending outwardly from said body member, electric light elements on the outer ends of said supporting arms, a ring having a tubular cross section connected to the upper portion of said body member and communicating with the interior thereof, a tubular rod-like element having means on the upper end thereof for securing said element to a ceiling and a hook on the lower end thereof with said ring being supported on said hook, there being a first opening in the inner face of said hook adjacent said ring and a second opening in said ring registering with said first opening, flexible electrical conductors extending from said electric

light elements through said supporting arms, said body member, said ring and through said openings into said rod-like element so as to be concealed from view when said chandelier light fixture is mounted in position from a ceiling, a ceiling plate on the upper end of said rod-like element and positionable against the ceiling, and means on said ceiling plate for locking said ceiling plate in position on said rod-like element.

5. A chandelier light fixture comprising a hollow body member, a plurality of hollow supporting arms extending outwardly from said body member, electric light elements on the outer ends of said supporting arms, a ring having a tubular cross section connected to the upper portion of said body member and communicating with the interior thereof, a tubular rod-like element having means on the upper end thereof for securing said element to a ceiling and a hook on the lower end thereof with said ring being supported on said hook, there being a first opening in the inner face of said hook adjacent said ring and a second opening in said ring registering with said first opening, flexible electrical conductors extending from said electric light elements through said supporting arms, said body member, said ring and through said openings into said rod-like element so as to be concealed from view when said chandelier light fixture is mounted in position from a ceiling, a dome-shaped ceiling plate having a central aperture therein for slidably receiving the upper end of said rod-like element with the concave side of said ceiling plate being positionable against the ceiling, a vertical plate within said ceiling plate adjacent said aperture, and means within said ceiling plate for urging said rod-like element tightly against said vertical plate to position said ceiling plate on said rod-like element.

6. A chandelier light fixture comprising a hollow body member, a plurality of hollow supporting arms extending outwardly from said body member, electric light elements on the outer ends of said supporting arms, a ring having a tubular cross section connected to the upper portion of said body member and communicating with the interior thereof, a tubular rod-like element having means on the upper end thereof for securing said element to a ceiling and a hook on the lower end thereof with said ring being supported on said hook, there being a first opening in the inner face of said hook adjacent said ring and a second opening in said ring registering with said first opening, flexible electrical conductors extending from said electric light elements through said supporting arms, said body member, said ring and through said openings

into said rod-like element so as to be concealed from view when said chandelier light fixture is mounted in position from a ceiling, a dome-shaped ceiling plate having a central aperture therein for slidably receiving the upper end of said rod-like element with the concave side of said ceiling plate being positionable against the ceiling, a vertical plate within said ceiling plate adjacent said aperture, an inclined plate within said ceiling plate adjacent said aperture and opposed from said vertical plate, said inclined plate being inclined toward said aperture, a dowel between said rod-like element and said inclined plate, a spring urging said dowel downwardly against the inner surface of the ceiling plate, and means within said ceiling plate for wedging said dowel between said rod-like element and said inclined plate whereby said ceiling plate is locked in position on said rod-like element.

10 7. A chandelier light fixture as claimed in claim 6, wherein said wedging means comprises a set screw in said ceiling plate engageable with said dowel to wedge said dowel between said rod-like element and said inclined plate whereby said ceiling plate is locked in position on said rod-like element.

15 8. An arrangement for positioning an apertured ceiling plate on a rod-like element passing therethrough and comprising a dome-shaped ceiling plate having a central aperture therein for slidably receiving the upper end of said rod-like element with the concave side of said ceiling plate being positionable against the ceiling, a vertical plate within said ceiling plate adjacent said aperture, an inclined plate within said ceiling plate adjacent said aperture and opposed from said vertical plate, said inclined plate being inclined toward said aperture, a dowel between said rod-like element and said inclined plate, a spring urging said dowel downwardly against the inner surface of the ceiling plate, and a set screw in said ceiling plate engageable with said dowel and acting against the force of said spring to wedge said dowel between said rod-like element and said inclined plate whereby said ceiling plate is locked in position on said rod-like element.
